UNITED STATES PATENT OFFICE.

WILBERT F. LEWIS, OF TACOMA, WASHINGTON, ASSIGNOR OF FORTY ONE-HUNDREDTHS TO A. HYNDMAN.

FUEL-OIL-BURNER REGULATOR.

Application filed December 26, 1923. Serial No. 682,653.

To all whom it may concern:

Be it known that I, WILBERT F. LEWIS, a citizen of the United States, residing at Tacoma, county of Pierce, and State of Washington, have invented a new and useful Fuel-Oil-Burner Regulator; and I do hereby declare that the following is a full, clear, and exact specification, such as will enable others skilled in the art to which it appertains to make and use the same.

The invention is a means for automatically regulating the fuel and air of an oil burner.

The object of the invention is to provide a means for automatically regulating the admission of the fuel and air to an oil burner which will operate similar to a governor and admit the mixture as the pressure decreases and shut it off as the pressure increases.

With these ends in view the invention embodies needle valves, that may be placed in the steam and oil inlet passages and may be operated by a common stem which is connected to a piston in a cylinder that is connected to the boiler so that the piston will be affected by the pressure of the steam in the boiler. The stem between the needle valves is also provided with an equalizing spring and connected to one end of a walking beam, the opposite end of which is connected to a rod that is provided with a piston which is connected to the steam pipe, beyond the throttle valve, and said rod is also provided with an equalizing spring and connected to a valve by which the draft of the boiler may be regulated.

Other features and advantages of the invention will be seen from the following description taken in connection with the drawings, wherein:

Figure 1 is a sectional view through the casing.

Figure 2 is a cross section through the needle valve.

Figure 3 is a section similar to that shown in Figure 1 showing an alternate arrangement.

Figure 4 is a sectional plan showing the arrangement of the valves in the design shown in Figure 3.

In the drawings I have shown my regulator as it would be constructed wherein numeral 1 indicates the upper casing in which is a cylinder 2 that may be connected

to the boiler by a pipe 3. In the cylinder is a piston 4 that may be constructed with a head 5 having a flange 6 and a movable flange 7 which may be clamped against the head or packing rings 8 therein by a nut 9 on the piston rod 10. The rod may be screwed into a threaded hole 11 in the head 5. Below the piston is a sleeve 12 with flanges 13 at its ends which is also screwed on the rod 10 and free to move upward or downward as may be desired to adjust the movement; and below this sleeve is an enlarged portion 14 of the rod 10 which is threaded and provided with a nut 15 for holding a cap 16 of an equalizing spring 17 against the upper end of the spring. It will be seen that by turning the nut 15 it will be possible to adjust the tension of the spring. The spring 17 seats upon a web 18 in a casing 19 which forms a housing for the rod and is attached to the lower end of the upper casing 1. Below the web 18 is a cross-bar 20 as shown in Figure 2 which is adjustably held to the lower end of the rod 10 by nuts 21 and 22 and in which the needle valve stems 23 and 24 are screwed and adjustably held by nuts 25 and 26. The lower ends of the valve stems pass through stuffing boxes formed by nuts 27 and sleeves 28 which engage sections 29 of the lower or base casing 30 which is attached to the lower end of the casing 19. Below the stuffing boxes are openings 31 which are connected to oil and steam pipes 32 that may be screwed into the side of the casing as shown in Figure 1; and below the openings 31 are valve seats 33 through which the oil and steam may pass to openings 34 below and from these through pipes 35 and 36 to the burner. It will be seen that as the rod 10 moves upward and downward it will open and close the valves and thereby permit more or less oil and steam to pass through.

Between the flanges 13 on the sleeve 12 at the upper end of the rod 10 are knobs 37 of a walking beam 38 which is pivotally mounted in the casing and provided with knobs 39 at the opposite end which engage flanges 40 of a sleeve 41 that is similar to the sleeve 12. The walking beam 38 is mounted on a pin 42 and the sleeve 41 is screwed on a rod 43 so that the travel of the rod or walking beam in relation to each other may be adjusted by screwing the

sleeve upward or downward. On the upper end of the rod is a piston 44 similar to the piston 4 and in the cylinder 45 which is connected by the pipe 46 to the steam supply line at a point just beyond the throttle valve.

Below the sleeve 41 is an equalizing spring similar to the spring 17 and inside of this is a nut 47 which engages the upper surface of the web 18 of the casing to limit the downward movement of the rod 43. Below the web is another nut 48 which may be screwed upward or downward on the rod to limit its upward movement and at the lower end of the rod is a sleeve 49 which forms the inner cylinder of a sliding valve 50. This cylinder is constructed as shown in Figure 1 with large ports 51 adjacent its upper end, smaller ports 52 about midway of its length, and other smaller ports 53 at its lower end. Around the cylinder is a sleeve 54 which is also provided with large ports 55 adjacent its upper end, small ports 56 about midway of its length, and other small ports 57 adjacent its lower end. The base 30 which forms the lower casing of the regulator is provided with an opening in which the sleeve 54 is held and other openings around the sleeve which correspond with the ports and which are connected to outlet, inlet, and exhaust pipes. The opening 58 adjacent the upper end of the sleeve 54 corresponds with the openings 51 and 55 in the valve and sleeve and is connected to a pipe 59 which may be connected to the draft regulator in such a manner that as pressure is admitted to the pipe 59 the draft will be opened and as the pressure is shut off the draft will be closed, or partly closed as may be desired. Below the opening 58 is another opening 60 which is connected by a pipe 61 to the boiler or any suitable means for supplying pressure, and below the opening 60 is another opening 62 which corresponds to the ports 53 and 57 and is connected to an exhaust pipe 63.

In the design shown in Figure 3 the walking beam is omitted and the steam pipe 46 brought into the lower end of the cylinder 2 so that as the throttle valve is turned on steam will be admitted directly to the under side of the piston 4 and the piston will be forced to the upper end of the cylinder as shown and the valve at the lower end will be opened, thus permitting a full supply of the steam and oil and also the air to be admitted to the burner, and it will be seen that as the pressure of the steam in the boiler increases it will gradually force the piston downward and close the valve.

In the lower end of the cylinder is a threaded nut 64 which has a projection 65 on it upon which a nut 66 may be screwed to form a stuffing box. The arrangement of the valves at the lower end may be

changed as shown in Figure 4 so that all three of them may be operated by the movement of the rod 10; otherwise, the design is exactly the same as that shown in Figures 1 and 2.

It will be understood that changes may be made in the construction without departing from the spirit of the invention. One of which changes may be in the design of either of the casings; another may be in the design of the piston; another may be in the design or location of the walking beam; and still another may be in the type of valves used at the lower end.

The construction will be readily understood from the foregoing description. To use the device it may be assembled as shown with the pipe 3 connected to the boiler, the pipe 46 connected to the main steam line just beyond the throttle valve, one of the pipes 32 connected to the oil supply and the other to the boiler for supplying steam to the burner, the pipes 35 and 36 connected to the burner, the pipe 61 connected to the boiler or any suitable means for supplying pressure, the pipe 59 to the damper control, and the pipe 60 to any suitable point for exhaust.

The tension on the spring 17 will be adjusted so that normally the needle valves will just admit enough oil and steam to keep a low fire under the boiler or to keep the boiler at a given pressure, and as the pressure in the boiler increases or decreases the cylinder 2 which is connected to the boiler will operate the valves to admit more fuel to the burner as the pressure decreases and less fuel to the burner as the pressure increases. As an engine or other object which may be connected to the boiler is started by operating the throttle valve the steam from the supply line will pass through the pipe 46 to the cylinder 45 and force the piston 44 downward, which through the walking beam will force the rod 10 upward and open the needle valves. At the same time the rod 43 will force the valve 50 downward to the position shown in Figure 1 so that the ports 52 and 56 will be in line and admit steam from the pipe 61 to the interior of the valve. The ports 51 and 55 being elongated and therefore, always open will permit the steam to pass through the pipe 59 to the damper regulator and hold it open. It will be seen that as the rod 43 moves upward when the pressure is released the ports 52 and 56 will move out of alignment and the ports 53 and 57 will correspond so that the steam from the pipe 59 will pass through the valve to the exhaust pipe 60.

Having thus fully described the invention, what I claim as new and desire to secure by Letters Patent, is:—

1. A fuel oil burner regulator comprising needle valves inserted in the oil and steam

passages to the burner; a cylinder connected to the boiler so that as pressure in the boiler increases the cylinder will close the needle valves; a spring for equalizing the pressure on the cylinder; another cylinder connected to the steam supply line beyond the throttle valve; a walking beam for transmitting the movement of the piston in the latter cylinder to the piston in the former cylinder; and suitable valves operated by the movement of the cylinders for controlling a draft regulator.

2. A regulator of the type described having needle valves inserted in the steam and oil supply lines; a cylinder connected to a boiler for operating the needle valves; a spring for equalizing the movement of the piston in the cylinder; another cylinder working in combination with the former cylinder for opening the valves as an engine or other device operated by the boiler is started; a cylindrical valve also operated by the cylinder for regulating the draft; and suitable means for regulating the travel of the valve.

3. A device of the class described comprising valves in the oil and steam supply lines of a fuel oil burner; a cylinder for closing the valves as pressure in a boiler fired by the burner increases; a spring for opening the valves as the pressure in the boiler decreases; another cylinder, the piston of which is connected with the piston of the former cylinder by a walking beam for opening the valves as steam is drawn from the boiler; and other valves connected to the cylinders for regulating the flow of steam to a draft regulator.

4. A fuel oil burner regulator having needle valves located in the oil and steam supply lines of the burner; a casing having suitable ports therein to which inlet and outlet pipes may be connected, and suitable stuffing boxes for enclosing the valve stems; said valve stems being connected through a yoke to a rod, on the end of which is a piston and on which is also a flanged sleeve and a spring; said piston operating in a cylinder that is connected by a suitable pipe to the boiler, said spring being mounted so that it will counteract the boiler pressure, and said sleeve being connected to the end of a walking beam, the opposite end of which is attached to a similar sleeve on a piston of another cylinder, said latter cylinder being connected to the steam supply line leading to the boiler, said spring being mounted so that it will counteract the boiler pressure, and said sleeve being connected to the end of a walking beam, the opposite end of which is attached to a similar sleeve on a piston of another cylinder, said latter cylinder being connected to the steam supply line leading from the boiler at a point beyond the throttle valve; means on the piston rod of the latter cylinder for limiting the movements of the pistons; and cylindrical valves attached to the piston rod of the latter cylinder for regulating the flow of steam to a damper regulator and also for regulating the exhaust of the damper regulator.

beyond the throttle valve; means on the piston rod of the latter cylinder for limiting the movements of the pistons; and cylindrical valves attached to the piston rod of the latter cylinder for regulating the flow of steam to a damper regulator and also for regulating the exhaust of the damper regulator.

5. A fuel oil burner regulator having needle valves located in the oil and steam supply lines of the burner; said valve stems being connected through a yoke to a rod, on the end of which is a piston and on which is also a flanged sleeve and a spring; said piston operating in a cylinder that is connected by a suitable pipe to the boiler, said spring being mounted so that it will counteract the boiler pressure, and said sleeve being connected to the end of a walking beam, the opposite end of which is attached to a similar sleeve on a piston of another cylinder, said latter cylinder being connected to the steam supply line leading from the boiler at a point beyond the throttle valve; means on the piston rod of the latter cylinder for limiting the movements of the pistons; and cylindrical valves attached to the piston rod of the latter cylinder for regulating the flow of steam to a damper regulator and also for regulating the exhaust of the damper regulator.

6. A fuel oil burner regulator having needle valves located in the oil and steam supply lines of the burner; a casing having suitable ports therein to which inlet and outlet pipes may be connected, and suitable stuffing boxes for enclosing the valve stems; said valve stems being connected through a yoke to a rod, on the end of which is a piston and on which is also a flanged sleeve; said piston operating in a cylinder that is connected by a suitable pipe to the boiler, said piston having resilient means that will counteract the boiler pressure, and said sleeve being connected to the end of a walking beam, the opposite end of which is attached to a similar sleeve on a piston of another cylinder, said latter cylinder being connected to the steam supply line leading from the boiler at a point beyond the throttle valve; means on the piston rod of the latter cylinder for limiting the movements of the pistons; and cylindrical valves attached to the piston rod of the latter cylinder for regulating the flow of steam to a damper regulator and also for regulating the exhaust of the damper regulator.

WILBERT F. LEWIS.
